ELECTRIC LAMP

George E. Inman, East Cleveland, Ohio, assignor
to General Electric Company, a corporation of
New York

Application August 10, 1934, Serial No. 739,271

15 Claims. (Cl. 176—1)

This invention relates to electric lamps and the like, and especially to glow discharge vapor lamps such as the so-called low pressure "positive column" type or the "cathodic glow" type, giving diffuse rather than sharply localized or intense concentrated luminosity. The invention is concerned with lamps that contain a vaporizable working substance,—e. g., sodium and some other metals—and operate with very small vapor pressures of such substance. In such lamps, the absolute vapor pressure of the working substance is usually about 1 or 2 microns for sodium. Vapor pressures of low order are characteristic of the typical diffuse glow discharge, that generally appears to fill the whole lamp bulb. Very usually, such lamps contain a small amount of easily ionized gas, like neon, argon, etc., whose (partial) pressure in the lamp is around 1 or 2 to 7 mm., to assist in starting the sodium or other vapor discharge. This is the more desirable in lamps using a difficultly vaporizable working substance like sodium—as contrasted with one that is more easily vaporized like mercury.

Commercial sodium vapor lamps aim at operating temperatures around 250° C. for maximum efficiency; while the actual temperatures of their envelope or bulb walls range from about 220° C. or less to about 275° C. or more. The boiling point of sodium being about 877° C., the sodium vapor in the commercial lamp bulb is continually condensing on its inner surface and vaporizing again, with a tendency to accumulate and remain in any region or area that is relatively cool, because of the slower vaporization from the cooler region. This means that the sodium vapor pressure in the envelope will tend to fall below that corresponding to the general lamp temperature, and to approach that corresponding to the lowest temperature: i. e., that the lamp will virtually lack sodium, and its light output and efficiency suffer correspondingly. Or if the attempt is made to remedy this by forcing the lamp to operate at a higher current density in the glow discharge, and thus heat up its coolest region(s) to 250° C. or thereabout, then the general lamp temperature will be forced still higher, and the efficiency will also suffer.

Practically, it is very difficult to design a commercial lamp of the glow discharge type containing difficulty vaporizing metal so as to be evenly heated by its glow discharge; and the variation in wall temperature is apt to be even less favorable than the above-suggested range of 220° C. to 275° C. in the sodium vapor lamp.

While an adequate though small vapor pressure

of sodium or the like is essential to the operation of a glow discharge vapor lamp, and while the most favorable sodium pressure for efficiency is that corresponding to a (uniform) temperature of about 250° C., the current density in the glow discharge is also very important to the efficiency, and in a contrary sense: i. e., the lower the current density, the greater the luminous efficiency of the glow discharge. However, glow discharge currents that would be highly favorable from this point of view are insufficient to heat the lamp to the temperature that is most favorable as regards vapor pressure of a working substance such as sodium. This is so even when the sodium vapor lamp is operated in a double-walled vacuum jacket in order to conserve heat, as is customary.

Other limitations and drawbacks of such vapor lamps have lain in the necessity of a ballast resistance in series with the lamp, to control and limit rise of current through the lamp as it heats up; and of either providing compensating resistances, reactors, or transformers to allow such lamps to operate in parallel on ordinary (alternating current) lighting circuits of 110-120 volts—or else operating a plurality of the lamps in series.

I have found that these difficulties can be overcome, and a very high operating efficiency realized in a lamp of this general type, by supplying additional heat, as uniformly as possible or as nearly according to the deficiency in the various parts of the lamp as possible, so as to maintain a proper uniform lamp temperature with a relatively low glow discharge current, or current density. Preferably, and as hereinafter described, the lamp is heated externally. Suitable electrical heating means for this purpose may be operated independently, from a separate heating circuit, or may be adapted and used to ballast the lamp, or may be used to compensate for its low operating voltage. Useful light may be obtained from an incandescent body as well as heat; and the enhanced luminous efficiency of the glow discharge will largely, at least, make up for the relatively poor luminous efficiency of such a filament.

I also aim to provide a simple, compact, convenient lamp unit, needing no extrinsic accessories such as external ballast, compensating resistance, reactor, or transformer, and not even requiring the usual enclosing vacuum jacket; and to secure relatively high over-all efficiency of the whole unit. In a lamp unit of this character, I arrange for externally heating the glow discharge lamp envelope or bulb walls as uniformly as possible all over, partly by arranging a plurality of

glow discharge vapor lamps (or lamp tubes) in such close proximity to one another that they blanket one another's heat, and so heat one another, and partly by other external heating means 5 enclosed in an evacuated light permeable outer envelope or bulb along with the glow discharge lamp means (lamps or lamp tubes), and preferably arranged to throw their heat on the unblanketed or outward-facing walls of the closely 10 grouped glow discharge lamp means. A particularly favorable combination is to alternate lamps or tubes and heating means in a more or less regular, symmetrical arrangement with respect to a common axis. I have here particularly illustrated and described my invention as applied to one or more glow discharge lamps of cylindrical or tubular form enclosed with the external heating means in a cylindrical or tubular evacuated outer envelope; but while the cylindrical or tubular shape lends itself very advantageously to my purpose, it is not essential, and the invention in its broader aspects can be adapted to other shapes of glow discharge lamp and outer envelope.

25 I aim, furthermore, to provide light of improved quality by combining different light color tones (produced either in the same glow discharge lamp, or in separate glow discharge lamps) with two or more different ones of such 30 working substances as sodium, potassium, or other alkali metal, mercury, cadmium, calcium, or magnesium, etc.; also by combining the light of solid filaments or glow bodies with glow discharge vapor lamp light. Either or both of these 35 measures may be employed in lighting units such as referred to in the preceding paragraph.

Various other features and advantages of the invention will appear from the following description of species thereof, and from the drawings.

40 In the drawings, Fig. 1 is a side view of one form of lamp unit embodying my invention; Fig. 2 is a view of the "mount" of the unit shown in Fig. 1 at right angles to Fig. 1, without the outer 45 enclosing envelope or the contact terminals of Fig. 1; Fig. 3 is a somewhat diagrammatic plan view of the mount; Fig. 4 is a view similar to Fig. 1 illustrating a lamp unit of somewhat different construction, with an electrode of one of its glow discharge lamps in axial vertical section; Fig. 5 is a plan view of the unit shown in Fig. 4; Fig. 6 is a fragmentary plan view with certain parts in horizontal section as indicated by the line and arrow 6-6 in Fig. 4; Fig. 7 is a 50 side view of another lamp unit construction embodying my invention, with some parts in vertical mid-section; Fig. 8 is a plan view of the unit shown in Fig. 7; Fig. 9 is a side view of yet another lamp unit construction embodying my invention; Fig. 10 is a schematic wiring diagram of the embodiment of the invention illustrated in Figs. 1 to 3 and the embodiment of the invention illustrated in Figs. 4 to 6 and Fig. 11 is a 55 schematic wiring diagram of the embodiment of the invention illustrated in Figs. 7 and 8 and the embodiment of the invention illustrated in Fig. 9.

The device shown in Figs. 1-3 comprises elongated, tubular glow discharge vapor lamps 10, 10 and filaments 11, 11 arranged in alternation, at 60 substantially uniform intervals, and in symmetry with respect to a common axis or center. This gives a substantially uniform distribution of light and heat. As only two lamp tubes 10, 10 and two filaments 11, 11 are used in this particular device, the arrangement is a quadrated

one: i. e., the line of centers or common plane of the tubes is at right angles to that of the filaments. The filaments 11, 11 are outside the space between the lamps 10, 10, so as to throw their heat directly on the external lamp walls that are not blanketed and heated by the lamps themselves. Lamps 10, 10 (or their discharge gaps) and filaments 11, 11 extend in the same general direction, substantially or approximately parallel. Lamps 10 and filaments 11 are all enclosed in an evacuated and sealed (glass) envelope 5 10 or bulb 12, of tubular form, which not only protects the filaments from the atmospheric oxygen, but also minimizes radiation and loss of heat from the lamps, as well as from the filaments. 15 The filaments 11, 11 are preferably of tungsten, or other material having a positive temperature-resistance coefficient.

In the present instance, the device is shown equipped with a unitary base and contact terminal structure 13 which in effect forms part of the outer envelope 12 itself, rather than with a separate base secured to an envelope complete in itself, apart from the base. This structure 13 20 comprises a cup-like body 14 of glass with downward projecting hollow nipples 15, 15 to which are fused hollow metal terminal posts or thimble-sleeves 16, 16 closed at their lower ends. Such a unitary contact terminal structure is commonly known in the art as a "bi-post base." Metal current leads 17, 17, preferably of channel section, are attached to the hollow contact terminals 16, 16 inside the latter, and extend up through the nipples 15, 15 into the cup-like body 14. There 25 these leads 17, 17 are offset (by double bends) 30 toward the center of the envelope 12, so as to extend inward close beside one another substantially or approximately along the center or axis of the envelope and of the assemblage of lamps 10, 10 and filaments 11, 11. In other words, the 35 lamps and filaments are arranged in a hollow configuration around the current leads 17, 17. The exhaust tip 18 on the glass body 14 is also 40 shown sealed off.

The lamps 10, 10 are supported at their lower 45 ends by or from the structure 13, and at their upper ends by or from the upper or inner ends of the leads 17, 17. As here shown, each lamp 10 comprises as its envelope a glass tube with anularly shouldered or ridged metal contact discs 18, 18, fused to its ends. In the particular construction here illustrated, the lower ends of the lamps 10, 10 rest against an insulating bar or block 20 that extends diametrically across the interior of the cup-like body 14, this block 20 being 50 notched at 21, 21 to receive the ridge of each lower disc 18 and afford a "button" to engage inside this annular ridge. The upper end of each lamp 10 is held by a flexible wire spring finger 22 that has one end fastened to the upper end 55 of one of the leads 17, and has a circular loop 23 on its free end to engage around the annular ridge of the corresponding disc 18. Each spring finger 22 electrically connects its lead 17 to the upper contact 18 of its lamp 10, and presses the 60 ridge of the lower contact 18 against a sheet metal contact strip 24 that extends into one of the lower notches 21.

The filaments 11, 11 are mechanically supported from the current leads 17, 17 by means of uprights 25, 25 whence project suitable supporting arms. As shown in Fig. 2, each upright 25 65 comprises two separate wire sections which carry glass insulating beads 26, 27 and have their adjacent ends fused into a glass insulating and con- 70

necting bead 28. Lower and upper support arms 30, 31 are welded to the corresponding insulatively separated upper and lower sections of the upright 25 and to the ends of the filament 11, and serve as current connections for the filament 11. Intermediate support arms 32, 32 are fused into the glass beads 26, 27, 28 to serve as anchors. Each upright 25 is insulatively supported from the corresponding main current lead 17 by composite insulating arms 33, 33, whose wire sections are fused into glass insulating beads.

To ballast the lamps 10, 10, each of them is connected in series with one of the filaments 11, 11. While the resultant lamp-and-filament sets may be connected in parallel between the leads 17, 17, in the present instance I have shown them in series with one another between said leads, so that the device can be operated on standard lighting circuits of around 110 to 120 volts without being excessively large, or requiring excessively fine filaments 11, 11. For this purpose, the upper sections of the uprights 25, 25 are interconnected by a wire 35 extending across the upper end of the bulb 12, above or between the fingers 22, 22—indeed, this wire 35 and the sections of the uprights 25, 25 which it connects may consist of one single length of wire bent to an inverted U shape, as here shown—and the lower ends of the lower sections of the uprights 25, 25 are connected by wires 36, 36 to the contact strips 24, 24. Thus the filaments 11, 11 are connected in series between the lower ends of the lamps 10, 10, whose upper ends are connected to the leads 17, 17 as already described.

Recurring to Fig. 1, and referring to the internal features or mounts of the lamps 10, 10, it will be seen that each lamp has in the opposite ends of its tubular envelope the electrodes 40, 40, preferably of indirectly heated type such as known in the art. These electrodes 40, 40 are supported by an upright 41 comprising a main wire section and lower and upper wire L parts 42, 43 attached to said main section by insulating glass beads 44, 44 into which the parts are fused. From the main wire section project wire arms 45, 45 welded thereto, parallel with the arms of the parts 42, 43 and spaced from them about the length of the electrodes 40, 40. One electrode 40—or, more properly speaking, its internal heating resistance 46—is connected between the lower arms 42 and 45, and the other between the upper arms 43 and 45. An insulating refractory sleeve 47 (or a glass tube) surrounds the main section of upright 41 between the arms 45, 45. The lower arm 42 has welded thereto a wire support 48 that engages the lower disc 18 and electrically connects the arm thereto, and the upper arm 43 has a flexible electrical connection 49 to the upper disc 18. Thus the internal heating resistances 46, 46 of the electrodes 40, 40 are electrically connected in series between the lower and upper discs 18, 18.

To the insulating sleeve or tube 47 of each glow discharge lamp 10 is attached a hermetic capsule 50 containing a charge of sodium or other such vaporizable working substance for the lamp. This capsule 50 may be of glass hermetically sealed, and may be encased in a piece of thin-walled nickel tubing 51 crimped in at the ends to retain the capsule. The capsule 50 is thus installed on the mount of the lamp 10 before the mount is sealed into its tubular envelope. After the lamp 10 has been exhausted—and preferably after it has been sealed off—the metal-cased capsule 50 is brought into the field of a high frequency coil externally surrounding the lamp 10.

In this way the capsule 50 is heated up until the pressure of the sodium due to the heat generated in the metal casing 51 explodes or ruptures the capsule (which is softened by the heat), thus liberating the sodium in the tube. If the high frequency coil is powerful enough, the metal casing 51 may be dispensed with; although it is useful to retain the pieces of the ruptured capsule. If preferred, the rupturing of the capsule 50 may be done after the lamps 10, 10 have been installed in the outer envelope 12, and the latter exhausted and sealed off.

Besides the charge of sodium or the like, each lamp 10 preferably contains a tenuous atmosphere of neon, argon, or other suitable gas that is readily ionized. This is introduced after the lamp 10 is exhausted, but before it is sealed off.

In the operation of the device, starting cold, the current flows at first through the electrode-heating resistances 46, 46 and the main section 20 of the upright 41 of each lamp 10, in series; but as the electrodes 40, 40 heat up, more and more current is carried by ions of the neon or other gas in the gap between them. As the whole lamp 10 heats up and vaporizes some sodium or other metal, the metal ions participate in the luminous discharge, in shunt with the resistances 46, 46 and upright 41. Besides being internally heated by its electrode-heaters 46, 46, and its glow discharge, each lamp 10 is externally heated by the adjacent lamp and by the filaments 11, 11, whose arrangement with reference to the lamps 10, 10 and the envelope 12 assures a very uniform distribution of this external heat to the lamp tube walls; since the heat of the filaments striking the walls of the outer envelope 12 obliquely is reflected and reradiated back on those portions of the lamp tube walls that receive the least heat directly. Thus the distribution of heat throughout the evacuated outer envelope 12 is very uniform. The vacuum in the envelope 12 minimizes loss of heat by conduction or convection. The efficient external heating of the lamps 10, 10 by the filaments 11, 11 helps to vaporize the sodium or other such working substance in the lamps. In other words, the heating means 11, 11 coact with the internal heat of the lamp from the glow discharge and the electrode heaters 40, 40 in heating the walls of the lamps 10 uniformly to a temperature sufficient to maintain an ample supply of the metallic vapor with a low glow discharge current density. This gives very much greater luminous glow discharge efficiency than if the lamp itself had to be forced in order to vaporize more sodium by the heat of the glow discharge; and thus the filaments 11, 11, though themselves generally inferior in luminous efficiency to the lamps 10, 10, nevertheless very greatly increase the overall efficiency of the whole device. Such a lamp may be operated at about 250° C. with a glow discharge energy consumption as low as about 0.1 watt per square centimeter of envelope surface. The filaments 11, 11 ballast the lamp 10, 10 very satisfactorily, as already explained.

The combination of the light of filaments 11, 11 of tungsten with the yellow light from sodium vapor gives a combined light of improved quality. By using one lamp 10 with sodium and another lamp 10 with a mercury or other metallic charge, along with filaments 11, 11 of tungsten or other material, a combined light of still better quality can be produced, by combination of the yellow sodium and the blue-green mercury light-tones with the (yellowish) white of tungsten. Also, two or more working substances may be

used together in either or both of the vapor lamps 10, 10, as, for example, sodium in one lamp, and mercury in both lamps; or sodium and mercury in one lamp, and cadmium and sodium and mercury in the other. Obviously, of course, more than two lamps 10 and more than two tungsten or other filaments 11 can be used in an arrangement similar to that of Figs. 1-3; with different substances in the respective lamps, such as sodium, mercury, and cadmium. More complete mixture of the different kinds or color-tones of light can be obtained by enclosing the device in a light-diffusing globe, or by frosting the envelope 12, or by a combination of such measures.

In Figs. 4-6, the arrangement of the tubular lamps 10a, 10a and filaments 11, 11 is similar to that shown in Figs. 1-3, but the mounting is different, as well as the construction of the lamps. In this instance, lamps 10a, 10a and filaments 11, 11 are all supported entirely from the main terminal post leads 17, 17. The filaments 11, 11 are not coextensive with the lamps 10a, 10a throughout their full lengths, as in Figs. 1 and 2, but only with the gaps between their electrodes 40a, 40a, or nearly so. Each lamp 10a has an all-glass envelope with current leads 53, 53 centrally sealed through its opposite ends and connected to the axially arranged glow-discharge electrodes 40a, 40a, which—or their internal heating resistances 46a, 46a—are interconnected by an axially extending (molybdenum) lead 41a, the upright 25 and associated parts of Figs. 1-3 being dispensed with. These electrodes 40a, 40a, are of internally emissive hollow type: i. e., each of them has its 30 electron-emissive material (such as barium oxide) on the inner surface of a (nickel) metal tube that is open toward the other electrode.

The lamps 10a, 10a are supported at their upper ends by or from the inner ends of the leads 40 17, 17, which extend side by side very much as in Figs. 1-3, but in the plane of the terminal posts 16, 16 instead of in a plane at right angles thereto. The leads 17, 17 are insulatively interconnected and spaced apart by braces 54, 54 45 welded to the leads near their lower and upper ends, each brace comprising wire sections fused into an insulative (glass) piece. Each lamp has its upper lead 53 attached and electrically connected to the horizontal arm of an (inverted) L-bent wire lead support 55 whose upright member is fastened to the end of its (channel) lead 17. An insulative (L-bent) brace 56 comprising wire sections fused into a (glass) insulating piece has one end welded to the outer end of a lead 53 55 and its other end fastened to the end of a (channel) lead 17. At the lower ends of the lamps 10a, 10a, there are two U or J-bent lead wires 57, 57, whose short limbs are welded to the lower lamp leads 53, 53, and whose long limbs extend upward in the plane of the filaments 11, 11, at right angles to that of the lamp tube axes, and midway between them. For the short limb of each J 57, there are insulative braces 58, 58 (similar to the braces 54 and 56 in construction), extending 60 from a common point on the J-limb to the two leads 17, 17. The lower end of each filament 11 is (electrically) connected to the upstanding long limb of a J 57, and its upper end is connected to the depending limb of an (inverted) U-bent lead wire 35 that extends horizontally across between the upper ends of the lamps 10a, 10a. The horizontal member of the U-bent lead wire 35 is shown in Fig. 5 as offset to one side of the plane of the filaments 11, 11, to keep it clear of the 70 leads 17, 17. The upstanding long limb of each

J wire 57 and the corresponding depending limb of the U-wire 35 are held in position by insulative braces 60, 60 (similar to the braces 54, 56, 58) welded to said limb and to the adjacent lead 17. Besides the lead supports 57 and 35, each 5 filament 11 may have an insulative anchor support 61, (similar to the braces 54, 56, 58, 60 in construction) welded to the adjacent lead 17 and embracing the filament about at mid-length.

Thus, it will be seen, the filaments 11, 11 are 10 connected in series with one another by the wire 35, and the serially connected pair of them is connected in series between the lamps 10a, 10a by the wires 51, 57. And the serial "chain" of lamp 10a, filaments 11, 11, and lamp 10a is connected in series between the terminal leads 17, 17 by the lamp leads 53, 53.

In the device shown in Figs. 7 and 8, the two lamp tubes 10b, 10b corresponding to the separate lamps 10, 10 of Figs. 1-3 and 4-6 are limbs 20 of a single (inverted) U-tube lamp, but are still arranged symmetrically and in alternation with the filaments 11, 11, as in Figs. 1-6. The U-lamp limbs 10b, 10b are supported entirely from the base and terminal structure 13, by means of separate saddle devices 20a, 20a, each consisting of a glass flare fused to the upper end of a metal sleeve 70 whose reduced lower portion extends down into one of the hollow contact terminals 16, and has an inward crimp 71 interlocked with a corresponding crimp of the terminal. The U-lamp 10b has an all-glass envelope with current leads 73, 73 sealed through its ends and connected to the axially arranged glow-discharge electrodes 40, 40, which—or their internal heating resistances 46c, 46c—are interconnected by a (molybdenum) lead 41b. The lead 41b is bent to lie against the inner wall of the U-bend of the lamp 10b. The (glass) ends of the lamp 10b may be fused to the (glass) flares of the saddle devices 20a, 20a. The filaments 11, 11 are only coextensive with the U-bent electrode gap, or approximately so. They are supported and interconnected at their upper ends by a (nickel) lead wire 25b coiled around the bend of the 45 U-lamp 10b about 1½ turns, with its end portions at opposite sides of the exhaust tip 74 on the lamp bend, and projecting beyond the sides of the lamp. The lower ends of the filament 11, 11 are welded to wire L-supports 24a, 24b which 50 are, in turn, externally welded to opposite sides of the saddle sleeves 70, 70, and extend upward beside one another near the axis of the envelope, etc., like the leads 24, 24 in Figs. 1-3 and 4-6. The support 24a forms a current lead connecting its filament 11 directly to the left-hand saddle sleeve 70 and terminal 16. The other support 24b, attached to the right-hand saddle sleeve 70, comprises two sections mechanically connected but insulated from one another by a 55 (glass) insulating piece 75, thus insulating the main section of this support from said sleeve 70. The left-hand electrode lead 73 extends down through the corresponding sleeve 70, out through a hole in the sleeve wall in which it is insulatively 60 sealed at 77, and then to the main section of the lead 24b, to which it is welded at 78. The right-hand electrode-lead 73 extends down in the corresponding sleeve 70 and is welded thereto at 79. Thus the filaments 11, 11 are connected in series 70 with one another and with the electrode gap 40, 40 of the U-lamp.

In manufacture, the U-lamp 10b with its internal parts is completed and exhausted, charged with neon or other gas and sodium or other work- 75

ing substance, and sealed off at 74. Then the saddle devices 20a, 20a, are attached and the lead coil 25b put in place. The filaments 11, 11 are installed and the electrode leads 73, 73 are arranged as described above and connected, one to the support 24b and the other to the right-hand saddle sleeve 70. The supports 24a, 24b may be welded to the sleeves 70, 70 either before or after attaching the saddles 20a, 20a to the lamp. The lamp and filament assembly is now mounted on the base 13 by inserting and securing the saddle sleeves 70, 70 in the base terminals 16, 16. The mount thus completed, it is inserted in the outer bulb 12 and sealed in, and the outer bulb is exhausted and sealed off at 18'. Holes 80, 80 in the sleeves 70, 70 allow their interiors to be exhausted.

Fig. 9 shows a U-lamp 10b like that of Figs. 7 and 8, supported entirely from the base 13 by a unitary saddle structure 25c, consisting of an (inverted) glass body resembling the body 14 of the base 13, but without the attached terminals 16, 16. The ends of the U-lamp limbs 10b, 10b are fused to the upper ends of the nipples 15, 15; but the exhaust tip 18' is left open to allow of exhausting the outer bulb 12 through the base tip 18' as usual. The lower filament lead supports 24c, 24c are fused through the bottom of the saddle body 25c. Within or below the saddle 25c, one support 24c is electrically connected to an offset terminal lead 17c (resembling one of the leads 17 in Figs. 1-3) by a springy helically wound lead wire 82, while the other support 24c has the (left-hand) electrode lead 73 welded to it. The other (right-hand) electrode lead 73 is electrically connected to the other terminal lead 17c, and includes a springy flexible helical portion 83. The upper ends of the terminal leads 17c, 17c are shown in the same horizontal plane, a little above the top of the base part 14.

In manufacture, the supports 24c, 24c, the lamp 10b with coiled lead 25b, and the filaments 11, 11 are all installed on the saddle 25c, and their connections completed as far as possible. This lamp and filament assembly is then placed over the base 13 and the leads 82 and 73 are cut to length and temporarily pinched to the leads 17c, 17c. Then saddle 25c is separated from base 13 slightly—helical lead portions 82 and 83 stretching to permit this—and the lead 82 is welded to its terminal lead 17c, and the (right-hand) lamp electrode lead 73 is welded to the other lead 17c. Then the saddle 25c is brought down against the base body 14—the helical lead portions 82 and 83 contracting to obviate any slack—and fused thereto around its periphery. The mount, thus completed, is inserted in the outer bulb 12 and sealed in, and the latter is then exhausted at 18' and sealed off.

60 What I claim as new and desire to secure by Letters Patent of the United States is:

1. A lamp unit comprising a plurality of glow discharge vapor lamp tube means close alongside one another, thus blanketing one another's heat; an evacuated outer envelope containing said lamp tube means in its vacuum space; and electric heating elements in said vacuum space, said lamp means and said heater elements being mounted about and at equal distances from a common center and in evenly spaced, alternate positions in said envelope, the heat from said heater elements coacting with the heat of the lamp tube means and with said outer envelope to heat the lamp tube means substantially uniformly to a temperature sufficient to maintain therein an ade-

quate atmosphere of vaporous working substance with a low glow discharge current density.

2. A lamp unit comprising a plurality of glow discharge vapor lamp tubes close alongside one another, thus blanketing one another's heat; 5 incandescent filament lengths extending alongside the adjacent unblanketed sides of said lamp tubes, said lamps and said filaments being mounted about and at equal distances from a common center and in evenly spaced alternate 10 positions about said center; and an evacuated envelope containing said lamp tubes and filament lengths and reflecting and reradiating the filament heat back on the outward-facing tube walls, so as to coact with the heat of the lamp 15 tubes in heating the tube walls substantially uniformly to a temperature sufficient to maintain therein an adequate atmosphere of vaporous working substance with a low glow discharge current density. 20

3. A lamp unit comprising a group of substantially parallel glow discharge vapor lamp tubes; a plurality of incandescent filament lengths connected in series with said lamp tubes as ballast and arranged in alternation with said lamp 25 tubes at equal distances therefrom and from a common center and substantially parallel with them; and an evacuated envelope enclosing said lamp tubes and filament lengths in its vacuum space. 30

4. A lamp unit comprising a pair of glow discharge vapor lamp tubes close alongside one another, thus blanketing one another's heat; a pair of incandescent filament lengths extending alongside said pair of lamp tubes at opposite 35 sides thereof, outside the space between them and at equal distances from a common center; and an evacuated envelope containing said lamp tubes and filament lengths in its vacuum space. 35

5. A lamp unit comprising a plurality of glow discharge vapor lamps containing different working substances which are vaporous in the operation of the lamps and give luminous glow-discharges of different color tones; a plurality of incandescent filament lengths connected in series 40 with said lamps to ballast them and arranged in alternation with the lamps and substantially parallel in direction with their discharge gaps; and an evacuated envelope enclosing said lamps and filament lengths in its vacuum space, said lamps and said filaments being at equal distances from a common center. 45

6. A lamp unit comprising a plurality of glow discharge vapor lamps and a plurality of incandescent filaments all connected in series with one another so that the filaments ballast the lamps and so that the combination can operate on ordinary standard lighting voltages; the filaments being arranged in alternation with the lamps about and at equal distances from a common center and being substantially parallel in direction with their discharge gaps, and an evacuated envelope enclosing said filaments and lamps in its vacuum space. 55

7. A lamp unit comprising an outer evacuated 60 envelope provided with contact terminals at one end; current leads connected to said terminals and extending inward close beside one another, substantially along the center of the envelope; a plurality of tubular glow discharge 65 vapor lamp tubes in said envelope arranged around said current leads, substantially parallel with them, and supported from them and electrically connected to them at their own inner ends; and a plurality of incandescent filament 70 75

lengths extending parallel with said lamps in said envelope adjacent said current leads and mechanically supported from the latter, and electrically connected in series with said lamps 5 to ballast them, said lamps and said filaments being in evenly spaced, alternate positions about a common center in said envelope.

8. A lamp unit mount comprising a unitary base and terminal structure; current leads attached to the terminals of said structure and extending therefrom side by side; a plurality of glow discharge vapor tubes extending substantially parallel and supported from the inner ends of said current leads and electrically connected thereto at their own inner ends, and supported at their other ends from said unitary structure; and a plurality of incandescent filament lengths having positive temperature resistance coefficients extending parallel with said lamps and electrically connected in series with the lamps to ballast them, said lamps and said filaments being in evenly spaced alternate positions about a common center.

9. A lamp unit mount comprising a unitary base and terminal structure, saddle means mounted thereon, glow discharge vapor lamp means mounted on said saddle means, filament supports and current leads also mounted on said saddle means, and incandescent filament lengths 30 attached and electrically connected to said filament supports and current leads, said vapor lamp means and said filament lengths being mounted in alternate positions about a common center.

10. A lamp and filament assembly comprising a glass saddle structure presenting seats for glow discharge vapor lamp tube ends, a glow discharge vapor lamp tube with its ends mounted on said seats, filament supports and current leads also mounted on said saddle means, and incandescent filament lengths attached and electrically connected to said filament supports and current leads, said lamp tube and said filament lengths being mounted in alternate positions about a common center.

45 11. The combination with a unitary base and terminal structure having a hollow projecting terminal post, of a glow discharge vapor lamp,

and a saddle attached to the end of said lamp and comprising a metal support member engaged in said hollow terminal post of said base and terminal structure, and electrically connected to an electrode of said glow discharge vapor lamp. 5

12. The combination with a unitary base and terminal structure having a hollow projecting terminal post, of a saddle comprising a hollow metal support member engaged in said hollow terminal post, and a glow discharge vapor lamp 10 attached to said saddle having a current lead extending through said hollow metal member and electrically connected thereto substantially at its end in said terminal post.

13. A lamp unit comprising an evacuated bulb 15 provided with contact terminal means at one end; a U-tube glow discharge vapor lamp mounted in said bulb with its ends toward said contact terminal means; and incandescent filament lengths in said bulb at opposite sides of said U-tube lamp, extending in the direction of its legs in a plane between the legs but outside the space between them, said legs and said filaments being at equal distances from a common center. 20

14. A lamp unit comprising an evacuated bulb 25 provided with base and contact terminal means at one end; a U-tube glow discharge vapor lamp mounted in said bulb with its leg ends attached to the based end thereof; a current lead attached to the U-bend of said lamp, with its ends projecting to either side thereof; and incandescent filaments in said bulb connected in series by said lead and extending therefrom toward the based end of the bulb, and also connected in series with the electrode gap of the U-lamp, said 30 legs and said filaments being at equal distances from a common center. 35

15. A lamp and filament assembly comprising saddle means, a U-tube glow discharge vapor lamp having its ends attached to said saddle means, filament supports and current leads mounted on said saddle means and on the U-tube bend, and incandescent filaments attached and electrically connected to said filament supports and current leads, the legs of said lamp 40 and said filaments being at equal distances from a common center. 45
